UNITED STATES PATENT OFFICE.

CARL E. TIDEMAN, OF WORCESTER, MASSACHUSETTS, ASSIGNOR TO E. W. BLISS COMPANY, OF BROOKLYN, NEW YORK, A CORPORATION OF WEST VIRGINIA.

WIREDRAWING BLOCK.

Application filed July 19, 1922. Serial No. 576,053.

To all whom it may concern:

Be it known that I, CARL E. TIDEMAN, a citizen of the United States, residing at Worcester, in the county of Worcester and 5 State of Massachusetts, have invented a new and useful Wiredrawing Block, of which the following is a specification.

This invention relates to a drum or block for winding or coiling wire on a wire 10 drawing machine or bench. It can be applied to the ordinary drums for drawing the wire through the dies or to the final drum on which the wire is wound after it has passed all the way through the 15 machine.

The principal object of the invention is to provide an effective and practical way of cooling the drums so that the heat generated from the successive passage of the 20 wires through a series of dies will be compensated for at the drums. Therefore, the wires will not be heated up more and more as it passes along from die to die in a continuous wire drawing machine.

Reference is to be had to the accompanying drawings, in which

Fig. 1 is a plan of a wire drawing drum with a preferred embodiment of this invention applied thereto;

Fig. 2 is a central sectional vertical view of the same;

Fig. 3 is a plan of the water supplying device in the drum; and

Fig. 4 is a transverse sectional view on 35 the line 4—4 of Fig. 3.

I am aware of the fact that it is well known that continuous wire drawing machines require the cooling of the drums for the reason that, as the wire passes each 40 die, considerable heat is generated.

Ordinarily, without water cooling, the temperature of the wire gradually increases by its passage through the several dies until it is so hot that it is injured by the 45 process. The principal idea of this invention is to provide improved means whereby the drums can be cooled adequately without expensive alterations. For this purpose I have shown a modified drum 10 for receiving the wire from a die. It is mounted on a vertical shaft 11. The outside of this drum is not materially modified but the bottom 12, which connects the hub 13 on the vertical shaft 11 with the outside, is 50 raised at the circumference. This provides

an external triangular annular groove 14 at the bottom, opening at the lower side of the drum. The drum is shown as usual considerably wider at the bottom than at the top and has this space 14 directly behind the conical surface on which the lower coils of wire are wound. This wire is heated to the highest degree and if properly cooled the wire at the top will not become overheated. This groove 14 can be made, if 60 desired, by welding two conical flanges in the bottom of a drum having a flat bottom. And I prefer to employ in addition two conical flanges 23 and 22 below the groove. 65

For the purpose of dissipating the heat, 70 the table or bench 15 is provided with a circular tank 16 in which is located a distributing pipe 17 of a circular shape receiving the water from any source of supply through an inlet 18 and discharging it 75 through an annular passage or outlet 19 which may extend all the way around the circle directly under the open bottom groove 14. This annular distributing pipe 17 is supported at one side by the integral inlet 80 pipe 18 which has been described. It is shown, opposite the inlet 18 as supplied with diverging feet 21 for firmly supporting it in horizontal position in the tank 16. This directs a circular sheet of water up 85 into contact with the interior surfaces of the groove and supplies a constant flow of water all around the drum, which is rotating all the time. The water thus discharged falls back into the tank 16 and 90 is allowed to drain off through an outlet 20. The flange 23 prevents the water being discharged inside and the flange 22 prevents its being forced outside by centrifugal force. The pipe distributes water to the groove 95 14 at all times during the wire drawing operation. This prevents the cumulative heating of the wire to such an extent as to injure the dies.

I have described this process of cooling 100 a drum of a continuous wire drawing machine, but the invention is not limited to a continuous wire drawing apparatus. I do not wish to be limited to the use of this invention for continuous wire drawing machine, as it is of great value for other similar wire drawing drums.

Although I have illustrated and described only one form of the invention, I am aware of the fact that modifications can be made. 110

therein by those skilled in the art without departing from the spirit and scope thereof as expressed in the claims, therefore, I do not wish to be limited to all the details herein described but what I do claim is:—

1. The combination with a rotary wire drawing drum, of a water distributing pipe located below the bottom thereof, and having an annular outlet opening extending toward the drum upwardly, and means for directing water into distributing pipe thereby by forcing it against the external lower surface of the drum.
- 15 2. The combination with a wire drawing drum having a conical outer surface, and an annular external groove at the bottom thereof behind the conical surface for receiving the wire, of a central distributing pipe located a distance below it, and having an annular outlet for discharging the water into the groove throughout the circumference thereof.
- 25 3. The combination with a conical wire drawing drum having an external inverted V-shaped groove surrounding the bottom thereof and open at the bottom, the lower

part of the conical wall of the drum constituting the outer wall of said groove, and means for directing a circular sheet of water into said groove to cool the bottom of the drum.

4. The combination with a wire drawing drum having a pair of circular diverging external flanges extending downwardly at the bottom forming a circular groove between them, of means for forcing a circular sheet of water between the flanges.

5. As an article of manufacture, a wire drawing drum having a conical external surface at the bottom for receiving wire and a pair of diverging circular flanges on the outside of the bottom thereof behind said conical surface.

6. As an article of manufacture, a drum for receiving wire thereon having an external circumferential groove in the bottom thereof and extending both above and below the surface on the drum for receiving the first coil of wire.

In testimony whereof I have hereunto affixed my signature.

CARL E. TIDEMAN.
